APPARATUS FOR MANUFACTURING TIRE CASINGS

Filed Sept. 24, 1928

INVENTOR.

By *Carroll O. Abbott Jr.*
Ernest Robinson
ATTORNEY

UNITED STATES PATENT OFFICE

ADRIAN O. ABBOTT, JR., OF DETROIT, MICHIGAN, ASSIGNOR TO MORGAN & WRIGHT, OF DETROIT, MICHIGAN, A CORPORATION OF MICHIGAN

APPARATUS FOR MANUFACTURING TIRE CASINGS

Application filed September 24, 1933. Serial No. 308,092.

This invention relates to a machine for forming a tire casing from a ring-like band of built up fabric and rubber known as a "pulley-band".

5 The present invention is an improvement over that disclosed in my Patent No. 1,507,563, granted Sept. 9, 1924.

An object of the invention is to provide a pulley band expanding machine with a novel 10 means for forming an air tight seal. It is also an object of the invention to provide a new and more convenient means for introducing the pulley band within the machine. 15 Other objects and advantages of the invention will appear in the detailed description which follows.

Without intending to limit the invention more than is required by the prior art, and with the specific embodiment herein disclosed 20 in mind, it consists in providing the casing of a "pulley-band" expanding machine with hinged end plates which may be opened to admit a pulley band and which are provided with apertures the edges of which are adapted 25 to contact with and form an air tight seal with the pulley band.

An understanding of the invention may be had from the following detailed description and the accompanying drawings in which:

30 Fig. 1 is a plan view of my machine;

Fig. 2 is a side elevation, partly in section, of my machine.

The casing of the machine consists of an annular side wall 1 to which is hinged at each 35 side a pair of end plates 3, 3 and 4, 4. The casing is supported upon the frame 2 in any suitable manner as by means of rivets.

Each pair of end plates 3, 3 and 4, 4 is provided with an aperture 5 the edge of which 40 is adapted to contact with a pulley band when in closed position as shown in Fig. 2. Sectors 6, 6 are attached to the plates 3, 3 through shafts 7, 7 which are pivotally connected to the side wall of the casing through brackets 45 7^a, 7^a.

Sectors 8, 8 are rigidly attached to end plates 4, 4 which are rotatably mounted on the side wall 1 as indicated at 9. The sectors 6 and 8 interengage in pairs as shown in Fig. 2 so as to coordinate the movement 50 of the end plates 3, 3 and 4, 4. Rod 10 inter-

connects the sectors 8, 8 through crank arms 11, 11. A lever 12 is rigidly attached to a crank arm 11 for manipulating the sectors 6, 6 and 8, 8 and thereby effecting the opening and closing of the end plates 3, 3 and 4, 4. 55

A platform 13 is provided upon which the pulley band may rest in proper relation with the casing when first inserted into the machine, this platform being mounted upon the frame 5 by the beams 14. 60

A source of suction is provided through the pipe system 15 connecting with the side wall 1 of the casing for exhausting the air therefrom. 65

In the operation of the machine the lever 12 is manipulated to open the end plates 3, 3 and 4, 4 into the position indicated in dotted lines in Fig. 2. A pulley band is inserted into the machine, its lower edge being placed upon the table 13. The lever 12 is again manipulated to close the end plates 3, 3 and 4, 4 bringing them into the position shown in full lines in Fig. 2. In this position the edges of the apertures 5 formed in each pair of the end plates contacts with the pulley band and forms a seal therewith sufficiently tight for the purpose. Suction is applied through the pipe system 15 to exhaust the air from the casing thereby causing the pulley band to be drawn from the form shown 70 in full lines in Fig. 2 to the form shown in dotted lines in that figure. A curing bag is then inserted into the casing, the lever 12 manipulated to open the end plates 3, 3 and 4, 4 and the casing with the curing bag removed 80 from the machine. 75

It is clear from the showing in the drawings and the above detailed description that a more convenient means for permitting the insertion of the pulley band in the machine 90 has been provided and that the means for creating a seal between the casing and the pulley band is of a more simple and more effective character than heretofore employed. 95

While I have disclosed specifically one embodiment of my invention, it is not intended to thereby limit my invention inasmuch as modifications obvious to one skilled in the art may be made therein all within the scope of my invention, and for an understanding of 100

the scope of my invention reference should be made to the following claims.

Having thus described my invention what I claim and desire to protect by Letters Patent is:

16. 1. In a pulley band expanding machine, an annular casing for expanding the pulley band, said casing having apertured end plates rotatably mounted thereon, adapted to be opened to receive the pulley band and to be closed to form a seal with the pulley band.
15. 2. In a pulley band expanding machine, a rigid ring, a pair of plates rotatably mounted on each end of the ring, each pair of said plates being provided with an opening the edges of which form a seal with the pulley band when in closed position, and which allows the passage of the pulley band when the plates are in open position.
20. 3. In a pulley band expanding machine, a casing having an annular side wall and a pair of plates hinged on each end thereof, each pair of said plates having an aperture adapted to admit the pulley band when in open position and adapted to form a seal with the pulley band when in closed position, means for manipulating said plates, and means for exhausting the air from said casing.
30. 4. In a pulley band expanding machine, a casing having an annular side wall, end plates therefor, and means for supporting said end plates comprising shafts, brackets for supporting said shafts from said annular casing, and means for rotating said shafts.
35. 5. In a pulley band expanding machine, a casing having an annular side wall, a pair of plates hinged on each end thereof, means for supporting said plates comprising separate shafts disposed at different positions at the ends of said casing, means for supporting said shafts, and means for simultaneously rotating all of said shafts.
40. 6. In a pulley band expanding machine, a casing having an annular side wall, a pair of hinged plates on each end thereof, supporting means for said plates comprising shafts, and means comprising a single operating handle for simultaneously rotating all of said shafts to cause said plates to close the casing.
45. 7. In a pulley band expanding machine, a casing, a pair of plates for closing one end of said casing, and means for simultaneously moving said plates to their open and closed positions.
50. 8. In a pulley band expanding machine, a casing, a pair of plates for closing one end of said casing, and means for simultaneously moving said plates to their open and closed positions, said means comprising a single operating handle, shafts for mounting said plates, and connecting means between said handle and shafts.
55. 9. In a pulley band expanding machine, a

casing, plates for closing the opposite ends of said casing, and means for causing the simultaneous movement of oppositely disposed plates comprising shafts, interlocking sectors and linkage means.

10. In a pulley band expanding machine, a casing, plates for closing an end of said casing, and mechanism for mounting and actuating said plates, said plates having complementary shaped edges for providing a sealed joint along their engaging edges.

Signed at Detroit, county of Wayne, State of Michigan, this 18th day of September, 1928.
